United States Patent Office.

ROBERT BERRYMAN, OF PHILADELPHIA, PENNSYLVANIA.

Letters Patent No. 80,328, dated July 28, 1868.

IMPROVEMENT IN INDICATORS FOR STEAM-GENERATORS.

The Schedule referred to in these Letters Patent and making part of the same.

TO ALL WHOM IT MAY CONCERN:

Be it known that I, ROBERT BERRYMAN, of Philadelphia, in the county of Philadelphia, and State of Pennsylvania, have invented a new and improved Combined High and Low-Pressure and High and Low-Water Indicator; and I do hereby declare that the following is a full, clear, and exact description thereof, which will enable others skilled in the art to make and use the same, reference being had to the accompanying drawing, forming a part of this specification.

The drawing represents a sectional elevation of my improved indicator.

This invention relates to improvements in alarm-indicators for steam-boilers, and consists in the arrangement of devices, as will be hereinafter more fully described.

Two valves are arranged in the upper part of the cylinder, one of which is raised by excessive pressure of steam, and acts as an ordinary safety-valve, while the other is lowered by a weight when either the pressure of steam or the quantity of water is reduced or falls below a given point. In either of these cases, when either of the valves is opened, a whistle will be blown, and the proper alarm given.

A, in the drawing, represents a cylindrical vessel, to be attached on any convenient point in front of a steam-boiler, of ordinary or suitable construction. It is, by means of two pipes, *a b*, connected with the boiler, the lower pipe, *a*, serving to keep the water in the vessel A at the same height at which it stands in the boiler, while the other upper pipe, *b*, conducts steam to the vessel A.

Upon the perforated cover *c* of the vessel A is secured an alarm-whistle, *B*, from which the steam is excluded by a valve, *d*, that is fastened to a vertical spindle, *C*, which extends nearly to the bottom of the vessel A, as shown. The spindle is drawn up by means of a weight, *D*, which is adjustably secured on a lever, *E*, which is secured to a fulcrum, *e*, attached to the whistle-bell sleeve, as shown. By means of this weight *D*, the valve *d* is drawn against its seat.

To the lower end of the spindle *C* is attached a weight, *F*, of soapstone, hollow metal, or of other suitable material, so as to be light. It is adjustable on the spindle, between two nuts, *ff*, as shown.

The lower end of the spindle passes through a guide, *g*, fastened to the bottom or sides of the vessel A.

When water is let into the vessel A, the weight *F* will become lighter, and when the steam enters the upper part of the vessel A, its pressure will, when all parts have been properly adjusted, suffice to hold the valve *d* against the seat. The weight *F* tends to draw the valve *d* down, but the combined action of the weight *D* and of the steam keeps it closed, provided the steam has the required pressure and the water its required height.

When the weight *F* is submerged, it is to a certain extent (or to about one-third of its weight) buoyed up and supported by the water. When the water falls below the required height, so that such support is withdrawn, the weight will open the valve, and the alarm will be given.

The required pressure of steam is determined by the position of the weight on the levers *E* and *H*, (the weight *F* being submerged in the water;) and when the pressure in the chamber is insufficient to hold the valve *d* to its seat, the valve will drop, and give the alarm; and when there is too great a pressure of steam, the safety-valve *G* will rise, and give the alarm.

Supposing the safety-valve to be adjusted to carry, say, fifty pounds of steam, the valve *d* will be so nearly balanced in its seat by the weight *D* on the lever *E*, and the submerged weight *F*, that a slight diminution in either the pressure of steam, or in the quantity of water, will open it, and the whistle will be blown.

Thus, by the aforesaid arrangement, alarm will be given when the water is too high or too low, or when the pressure of the steam is too low.

G represents a safety-valve, of ordinary construction, held down upon its seat by means of a weighted lever, *H*, as shown. The valve-spindle *h* fits in a whistle *I*, which is secured upon the cover of the vessel A. Excessive pressure of steam will open the valve *G*, and will blow the whistle *I*, thus giving the alarm.

By means of this invention all accidents can be avoided, and mistakes of negligence and oversight, cannot become dangerous.

By having the safety-valve G connected with a whistle, the alarm is not only given, but the useless waste of steam is prevented.

I am aware that the devices herein shown have been employed in alarm-indicators for steam-boilers, they are therefore not of my invention, and I do not claim them; but having thus described my invention,

What I claim as new, and desire to secure by Letters Patent, is—

The arrangement of the vessel A, spindle C, guide g, valve d, adjustable float F, whistle B, lever E, weight D, safety-valve G, weighted lever H, and whistle I, as herein described, for the purpose specified.

The above specification of my invention signed by me, this 7th day of March, 1868.

ROBERT BERRYMAN.
